Primary Examiner — Michael C Stout*Assistant Examiner* — Tia Ruth-Renee Polidori(57) **CLAIM**

The ornamental design for a bottle, as shown and described herein.

DESCRIPTION

FIG. 1 is an enlarged top perspective view of my new design for a bottle;

FIG. 2 is an enlarged bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is a front elevation view of my new design for a bottle with lid removed for clarity of disclosure; and,

FIG. 10 is a side elevation view thereof.

1 Claim, 6 Drawing Sheets(56)
